(57) **CLAIM**

The ornamental design for a display screen or portion thereof with animated graphical user interface, as shown and described.

DESCRIPTION

FIG. 1 is a first image in a sequence for a display screen or portion thereof with animated graphical user interface.

FIG. 2 is the second image thereof;

FIG. 3 is the third image thereof; and,

FIG. 4 is the fourth image thereof.

The appearance of the user interface sequentially transitions between the images shown in FIGS. 1–4. The process or period in which one image transitions to another forms no part of the claimed design.

The broken-line vertical rectangle illustrates a display screen. The broken-line outer perimeter illustrates an electronic device. The remaining broken lines illustrate portions of a graphical user interface. The broken lines form no part of the claimed design.

1 Claim, 4 Drawing Sheets
